UNITED STATES PATENT OFFICE

CHAIM CHESLER, OF CLEVELAND HEIGHTS, OHIO, ASSIGNOR TO THE METALLIC GRIPPER COMPANY, OF CLEVELAND, OHIO, A CORPORATION OF OHIO

GROMMET-FASTENED METALLIC GRIPPER

Application filed February 24, 1930. Serial No. 420,793.

My invention relates to new and useful improvements in grommet fastened metallic grippers which shall comprise integral metal portions designed to be bent, the one about 5 the other, and each of said metal portions having spaced apertures therein, in alignment both before the bending operation and after they are so bent, the apertures of one of said metal portions being in registration, 10 after the bending operation, with the apertures of the other portion, respectively, some means being employed to grip together the two metal portions which will ordinarily be metal plates comprising an elongated metal strip integral in all positions of said portions.

A common structure heretofore employed for reinforcing eyelets in canvas or similar material has comprised common grommets which are attached to the canvas singly, and 20 which structure has presented great difficulty due to the canvas having its several eyelets reinforced by single grommets, each of which will ordinarily bear its own strain separately, and which would be expected to tear out 25 of the opening in the goods successively, no one of the grommets serving to assist the others in carrying the load or strain designed to be applied to the given canvas.

A later improvement was invented by this 30 applicant which in general, was designed to apply plates to both surfaces of the material with their spaced apertures in registration when applied, and the grommets piercing the textile material and securing the two plates 35 together and thus applying the strain of all the eyelets in combination, which has been found desirable. This first improvement is disclosed in general in my application for metallic grippers filed January 24, 1930, as 40 Serial No. 423,162.

Since the filing of the above application, I have further improved the structure of the reinforced eyelets for bearing great strain applied to canvas and other textiles, by not 45 only making each of the plates above and below the textile, integral and positioning the several apertures in spaced relation on these plates, but I have further discovered that a further valuable advance in this art can readily be attained by forming the two plates

as an integral metallic strip, having apertures therein in spaced relation, and bending the integral strip about itself to bring the apertures in one portion in registry with those in the other.

This bending operation of the integral metallic strip upon itself and about the edge of the canvas, serves to hold the registered apertures of the plates in very exact registry, in addition to providing for further strengthening the material to which the grommet structure is to be applied. It will be noted, as the description of the structure proceeds, that such a bent metallic strip for this purpose may comprise a plurality of apertures 60 in each metallic portion of the plate, or that the integral strip may have but one aperture at either end, so that after the bending operation, there will be but one strengthened eyelet, but a single integral plate in any case.

With these and other objects in view, my improved construction outlined as my present invention consists in the structure described in the following specification, recited in the appended claims and illustrated in the accompanying drawing in which,

Figure 1 is a plan view of an elongated plate as one form of my gripper appears before its application to flexible material;

Figure 2 is a central longitudinal sectional view, such section being taken on the line 2—2 of Fig. 1;

Figure 3 is a plan view of the plate shown in Fig. 1 after having been applied to the edge of the material and secured thereon;

Figure 4 is a central longitudinal section taken on the line 4—4 of Fig. 3;

Figure 5 is a plan view of a metallic strip having spaced duplicate apertures;

Figure 6 is a longitudinal section in the plane indicated by the line 6—6 of Fig. 5;

Figure 7 is a plan view of the plate shown in Fig. 5 after being bent about the edge of the material;

Figure 8 is an axial sectional view of a grommet sleeve for insertion in the apertures of the plate shown in Fig. 7;

Figure 9 is a plan view of the plate such as shown in Fig. 7 after having been applied

to the edge of the material, and a grommet sleeve secured therein; and

Figure 10 is a longitudinal section of the structure shown in Fig. 9 taken along the 5 line 10—10 of said view.

Referring now especially to Figs. 1 to 4, an integral metallic plate 5 has a plurality of gripper structures 6 formed integral therewith and punched out from the plate, these 10 grippers being apertured and outwardly flanged from the latter to form annular seats therein, all said annular seats projecting from said plate in one direction and forming apertures 7 therein, and other gripper structures 15 8 integral with the plate and punched out therefrom in a direction opposite to the structures 6 and forming tubular or sleeve members in said plate. It is to be noted in Figs. 1 and 2 that the three gripper structures 20 6 as well as the tubes 8 are all spaced apart and all in alinement, the three tubes 8 being formed in one end of the plate 5 and the outwardly stamped grippers 6 in the opposite end. It is the purpose of this oppositely arranged structure to make possible the bending of the portion 9 of the plate having the tubes 8 downwardly, as shown in Figs. 1 and 2, about the edge of the canvas or other flexible material to which the gripper device is 25 to be applied, until such portion 9 will take the position directly beneath the portion 10 of the plate, but on the opposite side of the canvas, as shown in Fig. 3.

As the plate 5 is bent about the canvas, the 30 grommet tubes 8 will pass through the material, either through openings cut therein by said tubes during the bending operation of said plate 5, or through preformed openings in the canvas. The tubes 8 will then be inserted in the base of the punched out structures 6 and thence passed through the openings 7 of the apertured grippers 6 with which they register.

After the members 8 have been inserted in 40 the grippers 6, which members 8 extend somewhat above the members 6, because of the greater relative length of the sleeves 8, the material 11 and the bent plate are then positioned in a suitable press and the necks of the members 8 are overturned or upset to produce 45 encircling flanges 12 which engage the outward portions of the grippers 6 and press the opposite members 6 and 8 together permanently upon the canvas thereby very tightly gripping the canvas between the two plate portions 9 and 10, and thus forming as many eyelets as there are gripper structure 6, and the entire metal structure being integral.

In the structure shown in Figs. 2 and 4 and 50 above described, it will be seen that in forming the tubes 8 integral with the plate portion 9, the annular portions 13 of metal are first pressed upward to about the same height that the members 6 are formed in the plate portion 55 10, and then the longer tube portion 8

is directed downward, and is slightly smaller in diameter than the opening 7 of the member 6. This permits the ready entrance of the tubes 8 into the openings 7. In such structure, the grommet tubes 8 are integral with the plate portion 9, but the plate portions 9 and 10 are also integral with each other.

While the structure disclosed in the present invention has the integral bent portions 75 of the plate, one of said portions having integral grommet tubes, I have also shown in Figs. 5, 6, 7, 9 and 10, annular structures 15 punched out from the plate forming the apertures 16, and the securing grommets 17 80 formed of separate metal, as shown in Fig. 8 for insertion in the apertures 16, after the plate 14 is bent about the edge of the canvas.

This modified form of the invention while permitting the duplicate gripper members 15 85 to be integral with the plate 14, will require separate grommets 17 which are inserted after the bending operation of the metal, and the smaller end 18 of the part 17 to be overturned or upset to produce annular flanges 19 which will engage the annular structures 15, and thereby press the two portions of the plate 14 together and grip the canvas between such portions very tightly, as in the structure shown in Figs. 1 to 4.

It is evident that by the use of the lower metal plate integral with an upper metal portion, the combined strength of my integral but bent gripper structure will be greatly enhanced, and that the integral structure serves 100 the further valuable function of holding the punched-out flanges in registry, and thus make the desired position of the eyelet members more positive.

It is not my intention to limit my present 105 invention to any particular metal for the integral plates, nor to any particular number of eyelets in the plates, it only being essential that the integral plate may be bent upon itself in its middle portion without positioning the 110 line of fold across any of the apertures in the plate.

Having thus described my invention, what I claim and desire to secure by Letters Patent of the United States, is:

1. An eyeleting device comprising an elongated metal plate which may be bent upon a cross line thereof to form portions for engaging opposite faces of a piece of material, one portion having annular upturned and apertured gripper members struck up from the metal, and another portion having tubular neck members integral with the plate, spaced apart and all extending in parallelism in the same direction but opposite to that of said 120 gripper members, all of said gripper members and neck members being in alinement.

2. An eyeleting device comprising a metallic plate having a tubular neck portion integral therewith and pressed outwardly at an 125 130

angle to the plate for engaging a piece of flexible material, and an annular upturned gripper member having an aperture therethrough and spaced from the neck portion, the said neck portion being directed from the plate oppositely to the said upturned member while the plate is in a common plane, so that when the metallic plate is bent over the edge of said flexible material in a direction to move the neck portion toward the annular gripper member and the portions of the plate are pressed together with the flexible material between said portions of the plate, the neck portion will be forced in and through the apertured gripper member and extend beyond the latter to permit upsetting the neck portion to engage the gripper.

3. An eyeleting device comprising an elongated plate formed of flexible metal having tubular neck portions integral with the plate, spaced apart and all extending in the same direction in parallelism, and annular upturned and apertured gripper members in another portion of said plate and oppositely directed from said neck portions, so that when the plate is bent upon itself the tubular necks of one portion will enter the apertures of the other, and upsetting the outer ends of the necks will press the several neck portions and gripper members together and engage material between them.

In witness whereof, I have hereunto set my hand this 22nd day of February, A. D. 1930.

CHAIM CHESLER.
